M. MACDONALD.
HOLDER FOR TICKETS AND THE LIKE.
APPLICATION FILED OCT. 23, 1915.

1,309,255.

Patented July 8, 1919.

UNITED STATES PATENT OFFICE.

MURDOCK MACDONALD, OF CLEVELAND, OHIO.

HOLDER FOR TICKETS AND THE LIKE.

1,309,255.

Specification of Letters Patent. Patented July 8, 1919.

Application filed October 23, 1915. Serial No. 57,569.

To all whom it may concern:

Be it known that I, MURDOCK MACDONALD, a citizen of the United States, and a resident of Cleveland, county of Cuyahoga, and 5 State of Ohio, have invented a new and useful Improvement in Holders for Tickets and the like, of which the following is a specification, the principle of the invention being herein explained and the best mode 10 in which I have contemplated supplying that principle, so as to distinguish it from other inventions.

The present improvements relate to a ticket box adapted to receive and partially 15 inclose a pad of connected tickets and to retain and conceal within the casing the stubs of such tickets. Means are also provided for locking that side of the casing which carries the ticket pad in the same. 20 Also, an improved transfer slip is provided for use in connection with a device of the present type. To the accomplishment of the foregoing and related ends, said invention, then, consists of the means hereinafter 25 fully described and particularly pointed out in the claims.

The annexed drawings and the following description set forth in detail certain mechanism embodying the invention, such 30 closed means constituting, however, but one of various mechanical forms in which the principle of the invention may be used.

In said annexed drawings:—

Figure 1 is a front perspective view of 35 my improved ticket box; Fig. 2 is a rear view of the same; Fig. 3 is a transverse section on the line 3—3, Figs. 2 and 4; Fig. 4 is a plan view of the cover with the top thereof removed; Fig. 5 is a plan view 40 of an improved transfer form; Fig. 6 is a side view of the stub of the same; and Fig. 7 is a section on the line 7—7, Fig. 4.

The present ticket box has been designed to provide a simple means for retaining a 45 pad of tickets or transfers.

My device comprises a box-like structure 1, having an open side 2, which is normally covered by means of a cover plate hinged to the casing at 11 and consisting of two

hinged members 4 and 5 of which the member 4 is pivotally connected to the casing at one edge of the open side, while the member 5 is adapted to extend past the other edge of such side as indicated in Fig. 1. The two plates 4 and 5 are hinged together at 6, as stated, and are provided with springs 7, tending to swing the outer plate 5 about the hinge in a direction toward the casing. The two plates when extended are adapted to receive a pad of tickets 8, each 50 provided with apertures adapted to engage over pins 9 projecting from the plate 4, the pad then being held in place by means of a spring 10 connected to the hinge 11 between the member 4 and the casing as serving also to normally maintain the member 4 in an open position away from the casing. Means are provided on the member 4 for maintaining the plate 5 in such a position with respect to the open side of the casing 55 that the tickets are given a slightly arched position and are pressed against the free edge of the open side of the casing. These means comprise slideable rods 12 and 13, 60 movable longitudinally only in the casing 65 and operated by means of a movable button 10 on the outside of the member 4, and engaging behind the flanges 30 at the ends of the casing, (see Fig. 4.) The button 10 is connected by means of a sliding rod 31 70 to a pivoted plate 20 having curved slots 21 and 22 in which are received pins 23 on the ends of rods 12 and 13. The axis of the plate is at 24 and hence pivotal movement of the plate will cause the rods to be 75 moved out or in, as will be readily understood. The inner end 32 of the button 10 engages a spring 33 and in the locking position of the rods 12 and 13 is received in a recess 34 formed in the spring. 80

The present ticket box includes features long desired in such a device. The ordinary box now in general use, holds the pad of tickets in a bent position with the center of the bend against the tearing off edge. This 85 is necessary in order to maintain the tickets against this edge and to cause the stubs to snap back into the box but the result of the 90 95

bend is to cause the bottom tickets to be torn along a different line than the top ones. Attempts have been made to avoid this trouble by using the pad in its flat position, 5 but then the whole pad must be moved inward in order to free the stub from the edge and position it in the box. In the present device the pad is bent or arched very slightly, thus avoiding one difficulty 10 of the curved pad boxes, but is bendable in order to snap the stubs into position in the casing.

Upon the front side 15 of the casing there is mounted a longitudinally disposed slide 15 or rod 16, upon which are mounted slideable fingers 17, terminating in sharpened ends 18 which are adapted to produce notches in each ticket when torn off against this edge, these fingers being slideable along this rod 20 in order to produce these notches opposite any three desired names on the ticket. As each ticket is torn off, the operator presses the plate 4 inward, thus moving all of the tickets inward, and bringing the stub of 25 the ticket which has just been torn off, behind a longer flange 40 disposed behind the edge against which this ticket is drawn to tear the same. Upon such movement the stub engages behind this flange and is retained within the casing until the pad is 30 removed, thus preventing tampering with this stub by the conductor.

Referring to Fig. 5, there is shown a transfer provided with a duplicate series of numbers 21, arranged to show the hours of the day, followed by a duplicate series 22, showing quarter hours both before noon and afternoon, which is in turn followed by a 35 duplicate series 23, indicating the lines to which the transfers are to be given. These 40 duplicate series are so arranged on the transfer, that when a pad of these transfers is placed in the ticket box, the lower edge of the front side of the box is substantially 45 mid-way between the two series, so that the movable fingers will produce notches directly adjacent to the figures and names on the torn-off ticket, and will produce projections opposite the figures and names on 50 the stub. If these transfers are given out in the ordinary course, all of the projections 55 on the retained stubs will follow each other in a graduated line across the face of the pad of stubs as shown in Fig. 6, but if one or more of the transfers are issued 60 in advance of the regular time, the company's auditor can determine this fact by an inspection of the stub of the transfer pad, and by comparison of the same with the car record of the conductor to whom 65 such pad was issued, and is, of course, justified in assuming that these transfers that were issued in advance of the regular time 70 were to be used irregularly by some other

conductor, or were issued to friends to be 65 used at their convenience. Each conductor can thus be compelled to account for every transfer which he has issued, as the projections on the stub of the pad would have to correspond with the time given on the 70 car report for the issue of such transfers, allowing for whatever time is given the passenger to change from one line to another, which is, of course, always the same time, and is usually fifteen minutes. Not 75 only is the stub of the pad a complete record of the times for which the transfers were dated, but much time is saved by the conductors who receive them since each transfer shows at a glance the time issued and 80 the line to which the transfer is given.

Other modes of applying the principle of my invention may be employed instead of the one explained, change being made as regards the mechanism herein disclosed, 85 provided the means stated by any of the following claims or the equivalent of such stated means be employed.

I therefore particularly point out and distinctly claim as my invention:— 90

1. In a ticket box, the combination of a box-like casing open at one side, pad holding means hinged to one edge of such open side of said casing, said means comprising two hinged members and means adapted to 95 maintain said members in a position tending to produce a slight inward arch in said pad held thereon and against the other edge of such open side of said casing.

2. In a ticket box, the combination of a 100 box-like casing open at one side, pad holding means including a plate hinged to one edge of such open side of said casing, and a second plate hinged to said first named plate, means adapted to lock said first named 105 plate in substantially the plane of such open side of said casing, and means pressing said second plate toward the other edge of such open side of said casing and positioned at a slight angle to said first plate, thereby effecting a slight arch in a pad of tickets held on said plates. 110

3. In a ticket box, the combination of a box like casing open on one side, a pad holding plate covering such open side and pivoted to said casing at one edge thereof, said plate consisting of two hinged members, means tending to swing said members together toward said casing, means for maintaining said pad against the other edge of 115 such open side, indicating fingers movable along such edge and adapted to mark such tickets when torn off along such edge, and a projecting member adapted to maintain within said casing the stubs from such torn 120 tickets upon inward movement of such pivoted side. 125

4. In a ticket box, the combination of a

box like casing open at one side, a pad holding plate hinged to one edge of such open side and consisting of hinged members, one of which extends over the other edge of
5 such open side, means maintaining such members in a position producing a slight arch in said pad and forcing the same against the other edge of such side and means for maintaining within said casing

the stubs from such torn tickets upon inward movement of such pivoted side.

Signed by me this 21st day of October, 1915.

MURDOCK MACDONALD.
